MEANS FOR CONVERTING ACOUSTIC INTO
ELECTRIC ENERGY

Alexander Meissner, Berlin, Germany, assignor
to Telefunken Gesellschaft fur Drahtlose Tele-
graphie m. b. H., Berlin, Germany, a corpora-
tion of Germany

Application October 29, 1929, Serial No. 403,341,
and in Germany November 22, 1928

2 Claims. (CL. 179—121)

This invention relates to acoustic devices. More particularly it relates to acoustic devices in which the vibratile diaphragm is affected by standing waves or air columns.

5 Modern microphones when used for the broadcasting of high class music often exhibit the undesirable property that at some frequencies, especially relatively high frequencies, a standing wave is produced above the sound-impacted surface 10 or funnel shaped air columns are produced whereby the uniform operation of the instrument is impaired. These disturbances could be likened in some regards to disturbances or obstacles suffered by a current of air at surfaces (baffles) 15 placed in its path. Figure 1 shows these disturbances associated with an operation of a microphone which had a surface approximately three centimeters in diameter. Disturbing actions are clearly discernible at points A, B and C and these 20 are not due to natural vibrations of the microphone diaphragm, but are rather ascribable to the circumstance that standing air columns have been produced at these frequencies above the surface. Possibly also a sort of funnel has been 25 set up above the microphone surface at these frequencies at which the sound is deflected upon both sides (Figure 2) similarly as an air current.

Now, the ways and means here disclosed serve to obviate reflections and eddying upon the 30 surface of the microphone, or these actions are at least diminished to a large degree. The basic idea of the invention is that the surface receiving or impacted by the sound is provided with apertures through which the sound wave passes so 35 that the sound waves act upon the microphone surface without losing its character. If the active microphone surfaces are subdivided in a way as shown in Figure 3 the sound wave passes through the openings *a* thereof so that no standing 40 waves and disturbances are able to arise, upon the subdivisional small sized microphone surfaces. Also the disturbances due to eddies in the rear of the microphone surfaces are small if the relation between the useful or active surface 45 *b* and the section of the openings *a* is chosen correspondingly. A microphone surface or dia- phragm according to this invention would then

be of a nature as approximately shown in Figure 4.

The arrangement can be carried into effect most readily with microphones consisting of artificial piezo-electric substances, or of materials which serve as a dielectric for a condenser microphone. The shaded parts *b* in the illustration are the active surfaces, while the unshaded areas *a* constitute cavities. In order that all active surfaces may simultaneously act towards the outside, they are inter-connected by metal strips or bridge pieces. Upon the posterior face these microphone surfaces may be stiffened by suitable reinforcing strips as shown in Figure 5.

A technically simple arrangement is obtained 70 by disposing the active microphone surfaces strip-fashion adjacent to one another as shown in Figure 6. According to another modification wires are covered with active microphone layers, by securing thereon a cooperating electrode and causing the sound to impact upon this wire network. In this modification which is illustrated by Figure 7 the optimum relationship between wire diameter and opening (mesh) being selected so as to 75 suit a given frequency range.

In the above arrangement it is advisable to use either piezo-electric substances as the active microphone material in the form of plates, strips or wires, or else to have recourse to arrangements in which these substances are employed as fillers for the air-gap of a condenser microphone with or without additional biasing tension.

I claim:

1. A device for the conversion of sound energy into electrical energy comprising a non-uniform 90 surface adapted to be impacted by sound waves, said non-uniform surface being sub-divided by openings through which the sound wave is able to pass unimpededly.

2. A vibratile member for an acoustic device 95 comprising a plurality of different size surfaces spaced from each other and connected to each other by interconnecting strips, said surfaces being spaced from each other to provide openings through which a sound wave is able to pass 100 unimpededly.

ALEXANDER MEISSNER.
